UNITED STATES PATENT OFFICE.

CHARLES H. BELLAMY, OF SOUTH HADLEY FALLS, MASSACHUSETTS.

APPARATUS FOR GENERATING ACETYLENE GAS.

SPECIFICATION forming part of Letters Patent No. 592,759, dated November 2, 1897.

Application filed January 27, 1897. Serial No. 620,929. (No model.)

To all whom it may concern:

Be it known that I, CHARLES H. BELLAMY, a subject of the Queen of Great Britain, and a resident of South Hadley Falls, in the county 5 of Hampshire and State of Massachusetts, have invented certain new and useful Improvements in Apparatus for Generating and Burning Acetylene Gas, of which the following is a specification.

This invention relates to improvements in an apparatus for the generation and burning, for illuminating or other purposes, of acetylene gas, employing calcium carbid and means for supplying water thereupon, and particularly relates to an apparatus which comprises a closed generator chamber or receptacle in which the calcium carbid is placed, a separate water-receptacle above the generator, a suitable waterway or passage leading from the water-receptacle into the generator, together with means governed by the pressure of the gas as generated in the calcium-carbid receiver or generator for maintaining more or less open, or entirely closed, the said water-way, whereby the water will be automatically supplied and introduced into the generator as needed to maintain the desired quantity of generated acetylene gas, which shall be up to the pressure desired, such water-supply becoming at intervals diminished or discontinued as the supply and pressure of the generated acetylene become sufficient or excessive.

My present invention embodies, in an apparatus for generating and burning acetylene gas, a closed receiver-generator chamber, a water-receptacle, and a subreceptacle having a piston or plunger therein, the subreceptacle being connected with the main water-receptacle to receive water therein under the piston and said piston having a passage opening at its under side to the subchamber, which passage is continued in a suitable hollow stem or pipe of the piston into the generator-chamber, and a diaphragm or wall located in the generator-chamber and adapted to be movably controlled by the gas-pressure in the generator and connected with the said passage of the piston to correspondingly move it, all whereby the lowering of the pressure in the generator will permit the piston to descend,

displacing the water in the subreceptacle through the piston into the generator.

The invention further consists in an apparatus for generating and burning acetylene 55 gas, such as characterized in the statement of the nature of this invention, having further and also subordinate provisions and features of construction tending to increased efficiency and desirability of the apparatus, all as will 60 hereinafter fully appear, and be set forth in the claims.

Reference is to be had to the accompanying drawings, in which an apparatus exemplifying my invention is shown, Figure 1 being a central vertical section. Fig. 2 is a sectional view centrally through some of the parts drawn on a somewhat larger scale for purposes of clearer illustration.

The drawings here provided illustrate a 70 novel acetylene generating and burning apparatus comprising a closed generator A, in which may be received the calcium carbid, a water-receptacle B, a cylinder C, intermediately partitioned, double pistons *a* *a*², connected by a rod *b*, which plays through the cylinder-partition *h*, the piston *a* above the partition having a passage *d* therein which radially and downwardly leads to communication with the cylinder-space B², containing 8c water, between such piston and the cylinder-partition, which is the "subreceptacle" for water, as herein termed, said passage *d* continuing in the passage *d*² down through the stem or piston-rod *b* and through the lower 85 piston, a check-valved passage *i*, leading from the water-receptacle B into the subreceptacle B², said double piston of itself by reason of its weight constituting a suitable resistant against the gas-pressure which is exerted in 90 the generator-chamber against the lower piston, or which double piston has applied thereto a weight or spring *j*, as shown, to impart the suitable resistance against the gas-pressure, all whereby with suitably high gas-pressure or excessive pressure in the generator the double piston will be forced thereby in one direction, insuring a cessation of the passage of water through the aforementioned waterway, and whereby as the gas-pressure becomes diminished the piston *a*, descending under its weight or its spring, will effect a 95 100

displacement of the water in the subreceptacle B^2 through the waterway in the piston and piston-rod and a delivery thereof into the generator upon the calcium carbid.

5 The generator in which the calcium carbid may be placed is a sufficiently strong case or receptacle of any suitable form, the same being adapted to be closed, having, however, the openings k k^2 , one above the other, for 10 the introduction of the calcium carbid and for the withdrawal of the refuse. These covers are closed by the screw-clamps l l^2 . The water-receptacle B is supported upon the top of the generator, preferably by the screw connection seen at e . The base of the water-receptacle is here shown to constitute the top of the generator, and this base is centrally apertured, as seen at 12 , and supports the cylinder C , which has the upper and lower 15 cylinder-compartments f and g , divided by the cross-partition h . This cross-partition h is constituted by the central portion of a casting h^2 , which is in the form of a double cup, into which opposing cup-openings the cylinder-sections 13 14 are screwed. The upper piston has in its upper side the conical valve-seat 15 , which is at the upper end of tube-passage d^2 and at the junction therewith of the passage d , which leads radially through 20 the piston and downwardly opens at the under side thereof to the subreceptacle B^2 , as shown. The said conical valve-seat is surrounded by the hub 16 , which receives therein with a screw engagement the sleeve 18 , centrally bored and screw-threaded and having its bore terminate in the conical valve-seat 19 above valve-seat 15 .

The screw-rod 20 has on its lower end the double cone-valve m and at its upper end the 40 head to facilitate turning it. The double valve m may be turned and screwed up to close in the upper valve-seat 19 , then leaving passage d d^2 continuous and open, or the valve m may close with its seat 15 , shutting off the 45 passage of any water from the subreceptacle B^2 down through the piston-passage d^2 . The upper piston a has the depending hub or boss 22 , through which the passage d downwardly leads, receiving (screwing thereon) the thimble-shaped section 21 , which is internally formed with a seat for the conical check-valve 23 , which opens inwardly and permits the water to flow, as piston a is falling, through the central opening in the port d^3 in said 50 thimble-section 21 , whereby the water may in its displacement by the piston be forced through the piston and piston-rod or stem.

The subreceptacle B^2 has for its passages i , which lead thereto from the main water-receptacle B , inwardly-opening check-valves n , one or more, so provided and arranged that water may flow from chamber B into sub-chamber B^2 under the piston a , but so that as the piston has its downward movement or vibration the water in the subchamber cannot return to the main receptacle B , but can only pass through the port d^3 and passage d d^2 .

A practicable and efficient construction for the provision of the fittings for check-valves n consists in constructing external hubs 25 on the upper cup-like part of the said casting h^2 , drilled with the inleading passage or passages, as shown, and providing the cups or thimbles 27 , having the internal cone-seats for the valves n to screw on said bosses, each of the thimbles having a port 28 .

Stuffing-boxes 30 are advantageously though not necessarily provided where the piston-rod plays through the cylinder-partition h .

The lower piston a^2 , carried by the rod b , has the piston-rod passage d^2 continued therethrough, terminating in the downwardly-flaring conical valve-seat o , at which is equipped a check-valve p .

The thimble or check-valve case 33 screws onto the lower end hub of the piston and has ports 34 leading downwardly through it into the generator-chamber.

G represents the acetylene-gas pipe leading from the generator to any place to the exterior thereof and provided with a suitable burner G^2 . It will be seen that the lower piston a^2 is in substance a diaphragm or the wall of a collapsible chamber, the remainder of which chamber is constituted by the lower division of the cylinder and its partition, and that this piston-constituted diaphragm is susceptible of delicate vibratory action under inequalities in the gas-pressure in the generator, and in order that this delicacy of action may prevail I provide a means for relieving the piston-diaphragm of any effects of air-cushioning on its upward movement or vacuum on its descending movement. This, as shown, consists of a flexible, preferably elastic, sack, as a rubber bag q , in the receptacle B , connected by the tube q^2 with the cylinder-chamber between the partition h and the lower piston a^2 .

By turning the rod or stem 20 the valve m may be set down to close the passage d d^2 , so that the apparatus may at pleasure be rendered inoperative for the generation of acetylene gas at such times as the same is not being consumed at the burner or otherwise utilized by being withdrawn from the generator. On the other hand, when the valve m is raised, leaving the passage d d^2 open, it seats itself in the upper seat 19 therefor and effectually prevents the gas from working its way through the piston-rod to leak into the atmospheric air. This leakage is further prevented by the provision of the check-valve p at the bottom of the piston a^2 , this valve downwardly opening when the gas-pressure becomes lowered and the water is displaced from the subreceptacle B^2 by the then descending upper piston a , this said valve, when the gas-pressure is sufficient, being by such pressure held upwardly to its seat.

The check-valved passage or passages leading from the main water-receptacle into the subreceptacle B^2 , as is plain, permit the inflow

of the water from the main receptacle into the subreceptacle after water displacement from the latter and when the upper piston is rising.

5 Having thus described my invention, what I claim, and desire to secure by Letters Patent, is—

1. In an apparatus for generating and burning acetylene gas, a closed receiver-generator chamber, a water-receptacle and a subreceptacle, having a piston or plunger therein, the subreceptacle being connected with the main water-receptacle to receive water therein under the piston, and said piston having a passage, opening at its under side to the sub-chamber, which passage is continued in a suitable hollow stem or pipe of the piston, into the generator-chamber, and a diaphragm or wall located in the generator-chamber and adapted to be movably controlled by the gas-pressure in the generator and connected with the said passaged piston to correspondingly move it, all whereby the lowering of the pressure in the generator will permit the piston 25 to descend displacing the water in the sub-receptacle through the piston, into the generator, and a gas-pipe leading from the generator, substantially as described.

2. In an apparatus for generating and burning acetylene gas, a closed receiver-generator chamber, a water-receptacle and a subreceptacle, having a piston or plunger therein, the subreceptacle being connected with the main water-receptacle to receive water therein under the piston, and said piston having a passage, opening at its under side to the sub-chamber, which passage is continued in a suitable hollow stem or pipe of the piston, into the generator-chamber, a valve which, at pleasure may be operated to close the said passage in the piston against the passage of water from the subchamber therethrough, and a diaphragm or wall located in the generator-chamber and adapted to be movably controlled by the gas-pressure in the generator and connected with the said passaged piston to correspondingly move it, all whereby the lowering of the pressure in the generator will permit the piston to descend, displacing 50 the water in the subreceptacle through the piston into the generator, and the gas-pipe leading from the generator, substantially as described.

3. In an apparatus for generating and burn-

ing acetylene gas, a closed receiver-generator 55 chamber, a water-receptacle and a subreceptacle, having a piston or plunger therein, the subreceptacle being connected with the main water-receptacle to receive water therein under the piston, and said piston having a passage opening at its under side to the sub-chamber, which passage is continued in a suitable hollow stem or pipe of the piston, into the generator-chamber, and a collapsible chamber having a movable diaphragm or wall 65 located in the generator-chamber and said diaphragm adapted to be movably controlled by the gas-pressure in the generator, and connected with the said passaged piston to correspondingly move it, all whereby the lowering 70 of the pressure in the generator will permit the piston to descend, displacing the water in the subreceptacle through the piston into the generator, an elastic sack located outside of the generator and connected with said chamber having the movable or collapsible diaphragm-wall, and a gas-pipe leading from the generator, substantially as described.

4. In an apparatus for generating and burning acetylene gas, a closed generator-chamber, a water-receptacle and a subreceptacle, having a piston or plunger therein, a passage having a check-valve therein, which connects the subreceptacle with the main water-receptacle and said piston having a passage 85 opening at its under side to the subchamber, which passage is continued in a suitable hollow stem or pipe of the piston, into the generator-chamber, a downwardly-opening check-valve in said piston-stem passage and a diaphragm or wall located in the generator-chamber and adapted to be movably controlled by the gas-pressure in the generator and connected with the said passaged piston to correspondingly move it, all whereby the lowering 90 of the pressure in the generator will permit the piston to descend, displacing the water in the subreceptacle through the piston into the generator, and the gas-pipe leading from the generator, substantially as described. 100

In testimony that I claim the foregoing as my invention I have signed my name, in presence of two witnesses, this 25th day of January, 1897.
